Primary Examiner — Ricky Pham*(74) Attorney, Agent, or Firm* — Cook Alex Ltd.**CLAIM**

The ornamental design for a lid for a container, as shown and described.

DESCRIPTION

FIG. 1 is a top perspective view of a lid for container showing my new design;

FIG. 2 is a top plan view of the claimed design;

FIG. 3 is a bottom perspective view of the claimed design; and,

FIG. 4 is a side view of the claimed design, the other side is a mirror image.

The shading on the entire periphery of the container lid represents a color contrast with the center panel.

1 Claim, 4 Drawing Sheets(56)
